(57) CLAIM

The ornamental design for a beverage holder, as shown and described.

DESCRIPTION

FIG. 1 is a front perspective view of a beverage holder, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures illustrate portions of the beverage holder that form no part of the claimed design. The chain portion of the beverage holder has been shown with symbolic breaks. The appearance of any portion of the article between the break lines forms no part of the claimed design.
